UNITED STATES PATENT OFFICE.

WILLIAM S. BECHTOLD, OF NEWARK, NEW JERSEY.

BARRETTE

1,155,399.

Specification of Letters Patent.

Patented Oct. 5, 1915.

Application filed March 29, 1915. Serial No. 17,682.

To all whom it may concern:

Be it known that I, WILLIAM S. BECHTOLD, a citizen of the United States, and a resident of Newark, in the county of Essex and State of New Jersey, have invented certain new and useful Improvements in Barrettes, of which the following is a specification.

The invention relates to hair fasteners and ornaments, more particularly barrettes as employed to keep the loose and stray hair away from the neck of the wearer, as well as for use with braided hair.

It has for its object to provide a hair ornament of this character which shall have means additional to the usual pin or tongue employed for positively retaining the said barrette in the hair, whereby slipping of the barrette will be prevented and loss thereof after it is inserted in the hair obviated.

20 A further object of the invention is to so arrange these additional retaining means that the same shall be substantially invisible when the barrette has been arranged in position and thus not mar the effect of the barrette.

The nature of the invention will be best understood when described in connection with the accompanying drawings, in which—

Figure 1 is a front elevation of the improved barrette provided with additional retaining means. Fig. 2 is a transverse section thereof taken on the line 2—2, Fig. 1. Fig. 3 is a fragmentary front elevation illustrating a modification.

35 Similar characters of reference designate corresponding parts throughout the several views.

Referring to the drawings, 10 designates the body portion of the barrette and which may be of any suitable shape and desired ornamentation. The same is provided with the usual pin or tongue 11 hingedly connected at one end of the said body portion and is adapted to be locked in a suitable 45 catch 12 secured to the other end thereof, as is well understood.

In accordance with the present invention, a short comb or locking piece comprising a body member 15 and teeth or prongs 16 is secured to the back of the body portion 10 of

the barrette and substantially midway of its ends. The said teeth or prongs 16 are arranged to extend backwardly from the body 10 and are directed downwardly, either directly (Fig. 2) or at an angle (Fig. 3), 55 toward the tongue member 11, but do not extend beyond the said member. The thickness of the body portion 15 as well as the curvature of the teeth 16 extending therefrom is such that the comb is offset to some extent from the plane of the barrette body 10, whereby when the barrette is inserted into the hair of the wearer, the additional retaining portion will be substantially invisible being entirely covered by the hair. 65

In addition to the usual holding action of the tongue 11, it will be observed that the teeth 16, or rather the comb of which the teeth are a part, will serve to securely lock the barrette against any downward motion. 70 Moreover, a further holding action is obtained by the coöperation of the tongue 11 with teeth 16 themselves and between which the hair will be clamped. Owing to the fact that the said teeth do not extend beyond the tongue 11 and are suitably offset, no difficulty will be experienced in inserting the comb in the hair, nor will the said comb tend to become visible. 75

I claim:—

80 A barrette, comprising a back or body portion provided with a longitudinal opening, and a tongue pivotally attached thereto at one end, and adapted to be locked at the other end, a short comb portion extending rearwardly and downwardly from said back or body portion substantially to the middle thereof into the space between said tongue and body portion, and mid-way of the ends of the latter and substantially parallel thereto, whereby upon downward movement of the barrette said comb will bite deeper into the hair to lock the barrette against displacement, said comb also co-operating with the tongue to securely lock 90 the barrette.

95 Signed at New York, in the county of New York and State of New York, this 26th day of March, A. D. 1915.

WILLIAM S. BECHTOLD.
